ELECTRICAL TERMINAL BLOCK
Paul Huska, 739 Moreno, Los Angeles, Calif.
Filed June 1, 1962, Ser. No. 199,420
8 Claims. (Cl. 339—149)

This invention relates to electrical terminal blocks and is particularly concerned with electrically connecting separate conductors, two or more conductors, in a convenient and feasible manner.

Terminal blocks are made in varied forms some with metal posts, some with sockets, and some with clamps, all for receiving and/or securing the end or ends of one or more conductors. These blocks are characterized by a body of dielectric material that supports the conducting parts, and by means to clamp the conductors in place. Under operating conditions these blocks and their electrical connections are subjected to vibrations and severe heat changes, and it is not uncommon for conductors to become loosened. Needless to say a loose electrical connection aggravates the vibration and heat problems. Further, except by manually testing each conductor for tightness, it is impossible to make a visual check for proper electrical connections in a usual and ordinary terminal block of the type under consideration.

A general object of this invention is to provide clamp means in a terminal block of the type under consideration whereby proper connection or disconnection can be determined visually at a glance.

An object of this invention is to provide a new and improved two position clamp means in a terminal block of the character described. The clamp means hereinafter disclosed has a visibly released position and it has a visibly engaged position, and in the latter position the conductor or conductors are clamped in working position.

It is also an object of this invention to provide an inherent tightening action whereby the conductor or conductors are pulled into working position by the clamping action involved.

Another object of this invention is to provide a clamping means, as above set forth, that has a positive action and yet is operable to receive variations in conductor diameter or cross-section. As a result, variations in cross-section, size and/or shape does not adversely affect operation of the device within certain limits.

It is still another object of this invention to provide a positive mechanical motion that is converted into a pressing action, which action is transmitted through a multiplying means to apply clamping or pressured engagement in connecting electrical conductors.

The various objects and features of this invention will be fully understood from the following detailed description of the typical form and application thereof, throughout which description reference is made to the accompanying drawings, in which:

FIG. 1 is a perspective view showing the terminal block on its support, and indicating additional terminal blocks in phantom lines.

FIG. 2 is an enlarged detailed sectional view taken as indicated by line 2—2 on FIG. 1, showing but half the structure.

FIGS. 3, 4 and 5 are detailed sectional views taken as indicated by lines 3—3, 4—4 and 5—5 on FIG. 2, respectively.

FIG. 6 is a view similar to FIG. 3 and shows a modified form of the invention.

The terminal block B illustrated in the drawings is adapted to be used in multiples and said multiplicity of blocks assembled on a supporting channel C. The blocks B are therefore modularly formed, a typical block B being shown as having, generally, flat opposite sides 10, a top 11, a bottom 12, and flat opposite ends 13. The

2

bottom and top are essentially flat and parallel, with conductor openings 14 entering into the sides 10 at opposite sides of the block B. The ends 13 are adapted to engage flat against the next adjacent block B.

5 The channel C is an elongate support adapted to carry a multiplicity of block B in side by side relationship, with their ends 13 engaged with each other. As shown, the channel C opens upwardly, having a flat bottom 15 and opposite parallel side rails 16 with coplanar upper edges 17. The rails 16 are spaced apart a distance about equal to the width of the blocks B.

The terminal block B is characterized by a mounting means M underlying the block for engagement with the channel C. As shown, the means M is operable to attach and detach the block B to and from the channel C. In the preferred form, the means M involves opposite shoulder 18 for seated engagement on the opposite edges 17, said shoulders being stepped so as to have centering engagement with the channel C. In practice, the block 10 B has a depending boss 19 that extends between the shoulders 18, engaging between the side rails 16. Further, and in order to retain the block B in a working position, a bail 20 is provided at each side of the block to lock it on to the channel. The bail is shown as a spring biased detent 25 latch involving a leaf spring projecting from the block B and with a hook releasably engageable under the channel. It will be apparent how the bail can be manually deflected to release when so desired.

In accordance with the invention the block B is made 30 of a dielectric material, preferably molded in two half shells, as shown. Thus, the two shells can be assembled over the working components of the structure which involves, generally, an operator A, a pressure generating means D, a pressure multiplying means E, a clamp F, and a contact G.

The operator A is exposed at the top and side of the block B for manual operation and for visual observation. As shown, the block B is two sided with complete and identical conductor connecting mechanisms at each of the 40 opposite sides thereof, a description of one being sufficient for both. In order for the convenience of inserting a conductor into place, the opening 14 is upwardly and outwardly inclined and in which case the operator A is disposed above and parallel with said opening, or at the 45 same angle of inclination and exposed at the top-side corner of the block B.

The operator A is shown as a manually engageable element to be turned from an angular position to an aligned position. The operator A is characterized by a head 21 that is slotted so as to be rotated with a tool, such as a screwdriver, and only when the slot 22 is horizontally aligned, for example, with other horizontally aligned slots 22 are the said operators in pressure exerting positions, as later described. When in angular positions other than said horizontal positions, the said operators are released.

As shown, the operator A has a cylindrical body 23 underlying the head 21 to turn on the inclined axis, 60 above referred to. The body 23 is a cam element, a barrel-cam, with a pair of diametrically opposite cam faces 24 of equal helical pitch. The faces 24 are formed as by helically slotting the cylindrical body 23, each through $\frac{2}{3}$ (approximately) of the circumference and 65 suitably inclined as shown. In practice, there is a land or detent 25 at the top end of each cam face 24. Intermediate the head 21 and body 23 is an annular channel or groove 26 engageable with a corresponding ring-like projection formed in the shells of the body B, to retain the operator A in working position.

The pressure generating means D is provided to apply pressure under control of the operator A for use by the

means E in multiplying and exerting said pressure to the clamp F. The operator A and part of the means D occupy a bore 27 formed in the block B on said inclined axis. The operator A is rotatably retained in working position by the groove 26, above described. As is shown, the means D involves a resilient link 28 that extends between the operator A and pressure multiplying means E, to operate both in compression and in tension. The link 28 can vary in form and is shown as comprising a pair of bowed legs 29 to extend longitudinally of the axis of bore 27, there being a transverse pivot 30 joining the legs where connection is made to the means E, and there being a trunnion 31 projecting from each leg where connection is made to the operator A. It will be apparent that the bowed legs will straighten when the link 28 is put under tension, thereby establishing spring tension.

The pressure multiplying means E is provided to transfer the spring tension from means D to the clamp F, and reversely to retract the clamp F. In accordance with the invention the means E is a lever means, preferably comprising a pair of toggles 35 and 36. The upper toggle 35 is pivotally carried by the block B by a pin 37, while the lower toggle 36 is pivotally coupled to the clamp F by a pin 38. The transverse pivot 30 of the link 28 couples the overlapping ends of the toggles 35 and 36 so that shifting of the link causes articulation of the toggles, to angularly relate them or to straighten them. Thus, the clamp F is raised or lowered, and when lowered the pressure applied by the link 28 is augmented as the toggles reach a straightened condition.

With the structure thus far described the trunnions 31 are operatively engaged in the helically slotted barrel-cam body 23 to be moved thereby. It will be apparent that the operator A actuates the link 28 reciprocally between a relaxed or compressive condition and an actuated or tensioned condition. In practice, the shells of the block B are grooved at 27 in order to guide the legs 29, whereby turning of the operator A effects longitudinal movement of the link 28.

The clamp F is provided to be yieldingly urged into pressured engagement with the conductors K and is preferably a body 40 made up of dielectric material, like the block B, having an inclined clamp face 41. In accordance with the invention the clamp body 40 is guided vertically by vertically disposed chamber walls 42 in the block B, with the pin 38 centrally located at the top of the body 40. The face 41 is parallel with the inclination of the contact G which occupies the lower side of the opening 14, to oppose the said contact. As a result of this inclination with respect to the direction of movement of the clamp F, there is an inward and downward pinching of the conductors K when final pressure is applied by the clamp F. Further, the said final pressure is applied in a direction normal to the disposition of the inclined contact G.

The contact G is a body of conducting material, and in practice the clamp face 41 and contact G are both concave, or the like, for the wedging of a plurality of conductors K therebetween, as shown. The contacts G at opposite sides of the block B are continuations of each other, being joined by a transversely extending connector bar 45 integrally formed therewith. In accordance with good practice, a test post 46 is provided that connects with the bar 45 and extends upwardly to the top 11 of the block B where it is protected within a recess 47. By use of a probe in touching the post 46 it can be readily determined whether or not a good electrical connection is made.

In FIG. 6 a second form of invention is shown wherein the operator A' and pressure generating means D' are modified. This form of the invention employs a different type of spring means in the means D' and a

5 different form of cam means in the operator A'. As shown, the spring means is of helical form and is cooperatively related to and engaged with or in a screw formed within the body of the operator A'. The operator A' has an internal thread 50 threadedly receiving the helical coil 51 of the link 28'. The extended end of the spring link 28' carries a transverse pivot 30' that prevents turning of the spring and which operates the toggles 35 and 36 as above described. It will be apparent that the link 28' reciprocates upon turning of the operator A', and limited turning of said operator can be accomplished by providing a blind or abrupt end to the thread 50 in the operator that receives the helical spring coil. Also, limited opening action of the toggles will prevent disengagement of the link 28' from the operator A'.

From the foregoing the operation of the instant terminal block will be apparent. Not only are the conductors disposed at a convenient angle for ease of installation, but the clamping and/or release action is evidently apparent from a simple visual scanning of the many operators A that may be involved. When the slots of the operators are angularly disposed, the clamps F are retracted with a positive withdrawing action. When the slots of the operators are aligned, horizontally, the clamps F are yieldingly urged into pressure engagement with the conductors underlying the clamps F. It will be apparent that deformities no matter how caused, will be compensated for in the variable deflection of the links 28, while adequate pressure is maintained by the pressure augmenting toggles 35 and 36. As a result, vibration and thermal expansion and contraction do not adversely affect the electrical connections made by the device.

Having described only a typical preferred form and application of my invention, I do not wish to be limited or restricted to the specific details herein set forth, but wish to reserve to myself any modifications or variations that may appear to those skilled in the art and fall within the scope of the following claims.

Having described my invention, I claim:

1. A terminal block having terminals arranged back to back and disposed on inclined axes for the reception of upwardly inclined electrical conductors and including:
  - (a) a body having a pair of oppositely inclined openings therein for the reception of oppositely inclined electrical conductors,
  - (b) a pair of oppositely disposed manually actuatable operators at the exterior of the body and each on an axis parallel with one of said openings,
  - (c) a pair of clamps carried by the body and each operable in one of said openings therein normal to and to engage the said conductors respectively,
  - (d) and means coupling the respective operators and clamps, to move the clamps into and out of engagement with the conductors.
2. A terminal block having terminals arranged back to back and disposed on inclined axes for the reception of upwardly inclined electrical conductors and including:
  - (a) a body having a pair of oppositely inclined openings therein for the reception of oppositely inclined electrical conductors,
  - (b) a pair of oppositely disposed manually actuatable operators at the exterior of the body and each on an axis parallel with one of said openings,
  - (c) a pair of clamps carried by the body and each operable in one of said openings therein normal to and to engage the said conductors respectively,
  - (d) and resilient means coupling the respective operators and clamps to move the clamps into and out of pressured engagement with the conductors.
3. A terminal block for the reception of electrical conductors and including:
  - (a) a body having an opening therein for the reception of electrical conductors,

- (b) a manually actuatable operator at the exterior of the body,
- (c) a clamp carried by the body and operable into said opening therein to engage the conductors,
- (d) a toggle means comprising, an upper toggle pivotally carried to move in the body, and a lower toggle pivotally supporting the clamp,
- (e) and a resilient link pivotally joining the upper and lower toggles and yieldingly coupling them to the operator, to move the clamp into and out of engagement with the conductors.

4. A terminal block for the reception of electrical conductors and including:

- (a) a body having an opening therein for the reception of electrical conductors,
- (b) a rotatable operator with a head accessible at the exterior of the body and with a cam,
- (c) a clamp carried by the body and operable into said opening therein to engage the conductors,
- (d) and a means comprising movable, connected levers carried by the body and movably supporting the clamp, and a longitudinally resilient and movable link engaged with and extending between the cam and said levers, to be moved by the cam and to move the movably supported clamp into and out of engagement with the conductors.

5. A terminal block for the reception of electrical conductors and including:

- (a) a body having an opening therein for the reception of electrical conductors,
- (b) a rotatable operator with a head accessible at the exterior of the body and with a barrel-cam,
- (c) a clamp carried by the body and operable into said opening therein to engage the conductors,
- (d) and a means comprising movable, connected levers carried by the body and movably supporting the clamp, and a longitudinally resilient and movable link with trunnions engaged with the cam and extending between the cam and said levers, to be moved by the cam and to move the movably supported clamp into and out of engagement with the conductors.

6. A terminal block for the reception of electrical conductors and including:

- (a) a body having an opening therein for the reception of electrical conductors,
- (b) a rotatable operator with a head accessible at the exterior of the body and with opposite helically formed slots,
- (c) a clamp carried by the body and operable into said opening therein to engage the conductors,
- (d) and a means comprising movable, connected levers carried by the body and movably supporting the clamp, and a longitudinally resilient and movable link with oppositely disposed trunnions engaged in said opposite helically formed slots and extending between the operator and said levers, to be moved by rotation of the cam and to move the movably

supported clamp into and out of engagement with the conductors.

7. A terminal block for the reception of electrical conductors and including:

- (a) a body having an opening therein for the reception of electrical conductors,
- (b) a rotatable operator with a head accessible at the exterior of the body and with a cam,
- (c) a clamp carried by the body and operable into said opening therein to engage the conductors,
- (d) a means comprising movable, connected levers carried by the body and movably supporting the clamp,
- (e) and a resilient link extending between the operator and said levers and reciprocated by the cam to move the clamp into and out of yielding pressured engagement with the conductors.

8. A terminal block for the reception of electrical conductors and including:

- (a) a body having an opening therein for the reception of an electrical conductors,
- (b) a rotatable operator with a head accessible at the exterior of the body and with opposite helically formed slots,
- (c) a clamp carried by the body and operable into said opening therein to engage the conductors,
- (d) a pair of relatively movable, connected toggles carried by the body and supporting clamp,
- (e) and a resilient link extending between the operator and toggles with trunnions engaged with and reciprocated by the slots to move the clamp into and out of engagement with the conductors.
